NEEDLE THREAD TENSION DEVICE FOR SEWING MACHINES

Ralph Ernest Johnson, Mountainside, N.J., assignor to The Singer Manufacturing Company, Elizabeth, N.J., a corporation of New Jersey

Filed Oct. 25, 1957, Ser. No. 692,323

3 Claims. (Cl. 242—150)

The present invention relates to sewing machines and particularly to a needle thread tension device for sewing machines.

The United States patent of Chason, No. 2,131,005, illustrates a needle thread tension device that is widely used today. In such a device, the adjusting nut is limited to one revolution by means of a stop arm on an anchor disc that is locked against turning relative to the supporting stud or arbor and a cooperating lug on the outer spring cover which is in turn adjustably locked to the adjusting nut to provide for varying the range of action of the adjusting nut, by a connection including a pin on the adjusting nut and a plurality of holes in the spring cover.

In some decorative stitching a very light tension on the needle thread is required. In a tension device as illustrated in the Chason patent the pin and hole connection is held engaged by the action of the tension spring which biases the spring cover outwardly against the adjusting nut, so when the device is adjusted to a very light tension, there is a tendency for the pin to be dislodged from the aperture in the spring cover. When disengaged, there is freedom for relative movement between the adjusting nut and the spring cover, thus disturbing the setting and varying the range of action of the adjusting nut so that when normal tension is restored, the same angular positions as indicated by the indicia on the spring cover, do not represent the same amount of tension.

At the same time, adjustment of the range of action of the adjusting nut initially in manufacture or subsequently after it has been disturbed, is difficult since it requires moving the spring cover axially against the action of the tension spring to disengage the pin from the hole in the spring cover in which it is seated, and while holding it disengaged, effect the desired adjustment and then seat the pin in the corresponding hole. The available degree of adjustment is, of course, limited by the number of holes in the spring cover in which the pin on the adjusting nut can be seated.

In accordance with the above, it is an object of this invention to provide a needle thread tension device similar to that disclosed in the above noted Chason patent in which the tension adjusting nut is positively locked in adjusted position to the element that limits it to one revolution, thus precluding even at very light tensions the possibility of accidental relative displacement between them that would disturb the original tension settings.

It is also an object of this invention to provide in such a needle thread tension device, a construction in which adjustment of the range of action of the adjusting nut is facilitated and has an infinitely fine range of adjustment.

Having in mind the above and other objects that will be evident from an understanding of this disclosure, the invention comprises the devices, combinations and arrangements of parts as illustrated in the presently preferred embodiment of the invention which is hereinafter

2

set forth in such detail as to enable those skilled in the art readily to understand the function, operation, construction and advantages of it when read in conjunction with the accompanying drawings in which:

5 Fig. 1 is a sectional view of a needle thread tension device in accordance with this invention mounted upon a sewing machine.

Fig. 2 is an exploded perspective view of the elements of the tension device illustrated in Fig. 1.

10 With reference to the drawings there is illustrated at 1 a fragmentary portion of the wall of a sewing machine frame having a boss 2 on the inside thereof for accommodating a bore or recess 3 extending inwardly from the front face. There is provided a reduced diameter

15 bore 4 in the bottom of the recess 3, in which bore 4 the end of a cylindrical arbor 5 is mounted and in which it is adjustably secured by a set screw 6. Within the recess 3, the arbor 5 has an enlarged diameter portion

20 7 the periphery of which is provided with a plurality of longitudinally extending grooves 8 in a selected one of which is seated and thereby anchored the one end 9 of a check spring 10 coiled about the arbor and having at the other end a laterally extending thread engaging U-shaped portion 11 terminating in a loop 12 that is coiled about the arbor. The usual plate 13 is secured to the face of the wall 1 by a screw 14.

The disclosed tension device is designed to accommodate two needle threads and is therefore provided with thread-engaging means in the form of three tension discs

30 15, 16 and 17 having apertures in the center thereof for mounting them on the arbor 5, the center disc 16 being planar and acting as a separator between the oppositely dished outer discs 15 and 17. A guard plate 18 is mounted on the arbor 5 outwardly of the tension discs

35 and has an arm 19 seated in an aperture in the wall 1. The innermost tension disc 15 abuts against the shoulder provided at the outer end of the enlarged portion 7 of the arbor 5 and the discs 16 and 17 are resiliently urged against it by the guard plate 18 which is in turn biased

40 inwardly by the usual beehive spring 20 coiled about the arbor 5 and having the outer end thereof formed with a finger 21 that is seated in a slot 22 extending longitudinally inwardly from the free end of the arbor 5. Dis-

45 posed between the base or inner end of the spring 20 and the guard plate 18 is an inner spring cover 23 having a cylindrical side wall 24 and a base including a raised central portion 25 for positioning the base of the spring and having an aperture 26 for receiving the arbor 5.

The aperture 26 is traversed by a diameter bar 27 that

50 is seated in the slot 22 to hold the cover 23 against turning on the arbor 5.

The outer end of the spring 20 abuts against an anchor disc 28 having a central aperture 29 for mounting the disc on the arbor 5 and having a diameter bar 30 traversing the aperture 29 and seated in the slot 22 for securing the disc against turning on the arbor. The anchor disc 28

55 has a radially extending stop arm 31 that engages against a lug 32 on the inside of an outer spring cover 33 to limit turning of the cover 33 to one revolution. The cover member 33 comprises a centrally apertured flange or base 34 and a cylindrical side wall 35 that telescopes with the side wall 24 of the inner spring cover 23 to enclose the spring 20.

60 65 The free end of the arbor 5 is formed with external threads 36 which receives an internally threaded adjusting nut 37. The threads 36 and the cooperating threads on the adjusting nut are multiple, preferably sextuple, having a lead in one revolution equal to desired axial displacement of the adjusting nut. The inner end of the adjusting nut is formed with a flange 38 and the external surface thereof is provided with threads 39 for receiving a clamping nut 40. The outer spring cover 33 is

mounted on the adjusting nut 37 with the base 34 thereof secured between the shoulder defined by the flange 38 and the clamping nut 40 thus locking the cover 33 to the adjusting nut for rotation.

To lock the clamping nut 40 to the adjusting nut 37 to prevent accidental displacement thereof, the nut 40 is provided with a counterbore 41 defining an annular space between the nuts 37 and 40 and in which there is inserted a locking sleeve 42. A set screw 43 is threaded radially through the clamping nut to engage the locking sleeve 42 near the inner end thereof to lock the same between the nuts 37 and 40 into a binding relation and thus securely lock them together.

The arbor 5 is provided with the usual bore for receiving a tension releasing plunger 44 that engages against the bar 27 on the inner spring cover 23 to force it away from the tension discs against the action of the spring 20.

In operation, the spring 20 acting at its outer end against the adjusting nut 37, and acting at its inner end through the inner spring cover 23 and guard 18, biases the tension discs 15, 16 and 17 against the shoulder on the arbor 5 at the end of the enlarged portion 7 of the arbor 5. Turning the adjusting nut 37 will, of course, effect displacement of the same axially of the arbor 5, thereby varying the compression of the spring 20 and the bias imposed on the tension discs. Indicia such as the numerals 45 on the cover 33 and the mark or indicator 46 on the cover 23 serves to indicate the setting of the tension within the range of adjustment of the adjusting nut, turning of the adjusting nut being limited to the one revolution by the stop arm 31 of the anchor disc 28 and the cooperating stop lug 32 on the cover 33. The range of axial displacement of the adjusting nut 37 within this one revolution is determined by the initial setting of the adjusting nut and the position of the stop lug 32 relative to the stop arm 31 at the time the clamping nut secures the cover 33 to the adjusting nut.

With the construction as above described, the assembly of the tension and adjustment of the range of axial movement in one revolution has been substantially simplified. With the elements up to and including the anchor disc 28 assembled on the arbor 5, the adjusting nut 37 is then threaded onto the end of the arbors to approximately the desired setting corresponding to one of the end positions in the range of adjustment of the adjusting nut; for example, that position corresponding to minimum tension. The cover member 33 is then placed on the adjusting nut with the stop lug 32 engaged against the stop arm 31 on the side corresponding to minimum tension. The clamping nut 40 is then threaded onto the adjusting nut 37 to secure the cover 33 relative to the adjusting nut. Any further adjustments of the range of action of the adjusting nut that are desired can be effected simply by turning it to an intermediate position as indicated by the indicia 45, releasing the clamping nut 40, turning the cover in the desired direction, and then again securing the clamping nut in place. When the desired setting of the range has been accomplished, the locking sleeve 42 is inserted and locked by the set screw 43. At the same time, there is an infinite number of settings possible since adjustment of the spring cover 33 relative to the adjusting nut 37 is unlimited.

It will, of course, be obvious that the outer spring cover 33, which carries the stop lug 32 and thereby limits the adjusting nut 37 to one revolution, is positively secured to the adjusting nut by being clamped to the flange 38 of the adjusting nut by the clamping nut 40. Thus, even with a minimum tension setting there is no pos-

sibility of accidental displacement of the spring cover 33 relative to the adjusting nut 37 that would destroy the tension setting.

Numerous alterations of the structure herein disclosed will suggest themselves to those skilled in the art. However, it is to be understood that the present disclosure relates to a preferred embodiment of my invention which is for purposes of illustration only and not to be construed as a limitation of the invention. All such modifications which do not depart from the spirit of the invention are intended to be included within the scope of the appended claims.

Having thus set forth the nature of the invention, what I claim herein is:

15. A thread tension device for a sewing machine comprising an arbor, a pair of thread tension discs mounted on said arbor, an adjusting nut threaded on said arbor, a spring mounted on said arbor between said thread tension discs and said adjusting nut, a spring cover mounted on said adjusting nut and having a cylindrical sidewall enclosing said spring, means for limiting turning of said spring cover on said arbor to one revolution, and means for releasably securing said spring cover to said adjusting nut for unitary turning therewith on said arbor and for releasing said spring cover for turning on said arbor relatively to said adjusting nut, said means comprising a shoulder formed on said adjusting nut, an inwardly extending flange on said spring cover and seated on said shoulder, external threads formed on said adjusting nut, a clamping nut threaded on said adjusting nut for clamping said flange against said shoulder, and releasable locking means for securing said clamping nut on said adjusting nut.
20. 2. A thread tension device in accordance with claim 1 in which said means for limiting turning of said spring cover on said arbor to one revolution comprises an anchor disc mounted on said arbor and keyed to said arbor against turning relatively thereto, said anchor disc having a radially extending stop arm, and a stop lug on said spring cover and adapted to abut against said stop arm upon turning of said spring cover relatively to said anchor disc.
25. 3. A thread tension device for sewing machines comprising an arbor, thread-engaging means mounted on said arbor, an adjusting nut threaded on said arbor, a spring mounted on said arbor between said adjusting nut and said thread-engaging means, a member carried by said adjusting nut, means for limiting turning of said member on said arbor to one revolution, and means for securing said member to said adjusting nut in adjusted position comprising a shoulder on said adjusting nut and a clamping nut threaded on said adjusting nut for clamping said member against said shoulder, and means for locking said clamping nut comprising a sleeve, said clamping nut and adjusting nut being formed to provide an annular space therebetween at the free end thereof in which said sleeve is received, and a set screw threaded through said clamping nut and engaging the periphery of said sleeve adjacent to the one end thereof.
